(57) **CLAIM**

We claim the ornamental design for a model vehicle body mount, as shown and described.

DESCRIPTION

FIG. 1 is an upper, right, rear perspective view of a model vehicle body mount showing our new design;

FIG. 2 is a rear elevation view thereof;

FIG. 3 is a front elevation view thereof;

FIG. 4 is a left side elevation view thereof;

FIG. 5 is a right side elevation view thereof;

FIG. 6 is an upper plan view thereof;

FIG. 7 is a lower plan view thereof;

FIG. 8 is an upper, left, front perspective view thereof;

FIG. 9 is a lower, right, rear perspective view thereof; and,

FIG. 10 is a lower, right, front perspective view of the model vehicle body mount.

In the drawings, the broken lines illustrate portions of the model vehicle body mount that form no part of the claimed design.
